UNITED STATES PATENT OFFICE.

LUKE KAVANAUGH, OF WATERFORD, NEW YORK.

IMPROVEMENT IN BLADES FOR KNITTING-MACHINE SINKERS.

Specification forming part of Letters Patent No. 37,347, dated January 6, 1863.

To all whom it may concern:

Be it known that I, LUKE KAVANAUGH, of the village of Waterford, in the county of Saratoga and State of New York, have invented a new and useful Improvement in Blades for Yarn-Sinking Burrs of Knitting-Machines, of which invention the following is a full and exact description, reference being had to the annexed drawings, in which—

Figure 1 is a side view of one of my improved sinker-burr blades; Fig. 2, a side or end view of a sinker-burr having blades each like the one shown in Fig. 1; Fig. 3, an edge view of the burr shown in Fig. 2, engaged with and feeding yarn into needles of a knitting-machine; and Fig. 4, a section of a portion of the parts shown in Fig. 3, taken at the line $z z$ and viewed in the direction pointed by the arrow y , the same letters of reference indicating like parts in all the figures, and two varieties of my improved sinker-burr blade being shown by Figs. 5 and 6.

My improved blade for sinker-burrs of knitting-machines can be distinguished from all others by having through the blade A an opening, b , so located in respect to the notch or guide c for the yarn that in feeding and sinking the yarn x into and between the needles w in a knitting-machine by means of a sinker-burr having these improved blades the yarn with its knots and large spots in bending around the needles between the blades can then extend into the openings b in the blades, Fig. 4, so as to thereby leave more room between the blades for the needles, and make the blades have less tendency to bind between or against and bend or break the needles, and less liable to strain or break the yarn by pinch-

ing or nipping it between the needle and blade than if the blade were of the same outside shape and size but solid throughout, while at the same time the inner end, d , of the blade serves to brace or support the part c where the yarn is drawn over it, and also presents for the needle a continuous bearing beyond or clear of the yarn bending over the blade.

The shank e of my improved sinker-burr blade may be of any shape capable of being clamped, soldered, cast, or otherwise suitably fastened with a series of such blades in or to a hub, f , so as to thereby form a sinker-burr for a knitting-machine; and that part of the blade which is to project beyond the hub of the burr may be of any suitable outside form, and the opening b through the blade may have any suitable shape and sufficient size, even so that the blade will be a mere skeleton, as indicated in Fig. 6, in which case the blade may consist of a steel wire bent to the proper shape and hardened, provided that in all cases the opening b , or enough thereof, is so opposite to the yarn-guide c that in using a burr having such blades the yarn can enter or bend into the opening b in extending around a needle, as hereinbefore specified.

What I claim as new and of my invention, and desire to secure by Letters Patent, is—

A wing or blade for sinker-burrs of knitting-machines, having through it a hole or opening, b , arranged in respect to a yarn-guide, c , on the blade, substantially as herein described.

LUKE KAVANAUGH.
